ATTORNEY

UNITED STATES PATENT OFFICE.

GEORGE L. ALLEN, OF WORCESTER, MASSACHUSETTS.

STEAM-GENERATOR.

SPECIFICATION forming part of Letters Patent No. 341,716, dated May 11, 1836.

Application filed October 24, 1885. Serial No. 180,787. (No model.)

To all whom it may concern:

Be it known that I, GEORGE L. ALLEN, a citizen of the United States, residing at Worcester, in the county of Worcester and State 5 of Massachusetts, have invented certain new and useful Improvements in Steam-Generators; and I declare the following to be a description of my said invention, sufficiently full, clear, and exact to enable others skilled 10 in the art to which it appertains to make and use the same, reference being had to the accompanying drawings, which form a part of this specification.

The object of my present invention is to 15 provide a practical and convenient means of utilizing heat for raising the temperature of the return-water, and assisting the circulation in steam-generators which are employed for heating buildings and other purposes; and my 20 invention consists in the construction and arrangement of a hollow metal bridge-wall for the furnace, and its connection with the return-pipes and boiler in the peculiar manner shown, and hereinafter described.

25 In the drawings, Figure 1 is a longitudinal section of a steam-generator illustrating the nature of my invention. Fig. 2 is a horizontal section of the same above the grate and bridge. Fig. 3 is a transverse vertical section at line 30 *x x*, and Fig. 4 is a transverse vertical section at line *y y*.

In referring to parts, A indicates the boiler, made in arched form, with dependent water-legs *a a* along either side. B indicates the 35 brick-work or boiler-setting; C, the chimney-flue; D, the door-front; E, the entrance for cleaning the tubes; F, the furnace; G, the grate-bars, and H the steam-delivery, all of which parts may be constructed and arranged 40 in relation to each other substantially as shown.

Across the furnace F, at the back of the grates, I arrange a bridge-wall, I, which is made of metal in the form shown, with a low 45 interior space for containing water. Said bridge I is constructed with an upright front and sloping back, and with closed ends that fit between the dependent sides or water-legs

a a of the boiler, conveniently filling the space across the furnace. 50

To the lower part of the bridge I are connected the return-pipes J, that lead from the heating-radiators about the building, so that the water of condensation is returned into said bridge I before it enters the boiler. 55

From the upper part of the bridge I a pipe, K, extends backward and downward to a position near and below the rear end of the boiler, where it is provided with branches, as K', that extend laterally outward to the respective sides of the boiler, and there connect with the lower rear portion of the water-legs *a a* in the manner indicated. By this arrangement of the hollow bridge and pipes the return-water in the bridge becomes heated and 60 forces a circulation into the boiler through the pipe K, thereby utilizing heat, and also improving the general working of the generator, and effecting considerable economy in the use and efficiency of the apparatus. 65

Combined with one of the branch-pipes K is a blow-off pipe, L, leading out through the brick-work, and provided with the cock L', the arrangement of the pipes being such that the boiler and the hollow bridge are blown off 70 simultaneously through the pipes K, K', and L. 75

What I claim as of my invention, and desire to secure by Letters Patent, is—

1. The combination of the boiler A, the hollow bridge-wall I, the return pipe or pipes 80 J, leading into the lower part of said bridge, the pipe K, leading from upper part of said bridge, with branches K' communicating with the interior of the boiler at the lower rear part thereof, substantially as shown and described. 85

2. The combination of the boiler A, the hollow metal bridge I, the return-pipe J, the branched connecting-pipes K, and the blow-off L, leading from said connecting-pipe, as 90 shown and described.

Witness my hand this 7th day of October, A. D. 1885.

GEORGE L. ALLEN.
